IMPROVEMENT IN DEVICES FOR OPERATING THE SHUTTLES IN LOOMS.

JOSEPH J. AND EDWARD HARRISON, OF MANCHESTER, ENGLAND.

Letters Patent No. 59,767, dated November 20, 1866.

SPECIFICATION.

TO ALL WHOM IT MAY CONCERN:

Be it known that we, JOSEPH JOHN HARRISON and EDWARD HARRISON, of Manchester, Lancaster county, England, have invented certain Improvements in Looms for weaving, and we do hereby declare the following to be a full, clear, and exact description of the same, reference being had to the accompanying drawing and to the letters of reference marked thereon:

The invention relates to that part of the loom termed the "picking motion," and is designed for the purpose of dispensing with the picker and apparatus in connection therewith, as now employed, and substituting in lieu thereof a novel and improved arrangement of mechanism that shall give a more perfect and regular "pick" without the liability of "floating" the shuttle; and secondly, the invention relates to an improved arrangement of apparatus to be employed for retarding and checking the shuttle on its being received by the shuttle-box. This motion can be applied to looms for weaving of all descriptions. The arrangement and construction of apparatus for "picking" may be thus described: Two apertures formed in the back and front of the shuttle-box at their entrance nearest to the loom "reed" are constructed so as to receive and allow frictional bowls or pulleys to protrude through and enter the shuttle-box. These bowls are situated exactly opposite each other, and are supported and secured upon vertical spindles provided with wharves or pulleys which are driven at a high velocity through an arrangement of pulleys in connection with the crank shaft, which thereby gives a rapid revolution to the aforementioned frictional bowls in a direction outwards from the box. The spindles upon which these bowls are secured are supported on movable bearings, which are acted upon by a wedge in such a manner that the said bowls shall, when the wedge is inverted between their bearings, recede or separate from each other so as to allow the shuttle freely to enter the shuttle-box, when it becomes immediately "checked" by the improved eccentric check motion hereinafter described. So soon as this is effected the wedge is withdrawn from the spindle bearings, causing thereby the frictional bowl to close upon the shuttle, which effects the instantaneous expulsion of such shuttle into the opposite box, when it is received and again expelled in like manner. The shuttle, upon entering the box, is gradually and effectually checked by the improved eccentric "swell" before mentioned, the arrangement and construction of which may be thus described: A finger or rod secured to the stop-rod of the loom, and projecting upwards behind the shuttle-box, is provided with an eccentric disk or bowl having a projecting wing or finger. This eccentric works loose upon its aforesaid supporting rod, and is caused by the action of a spring, in connection with the stop-rod, to protrude or enter the shuttle-box, so that when the shuttle, as described, has passed the picking bowls, it is retarded and checked in its progress by the pressure against its side by the eccentric swell, the action of which upon the shuttle as such shuttle advances towards the head of the box is to give through its eccentricity an increased pressure thereupon, which effectually checks and prevents its further movement in that direction; but so soon as the picking bowls are caused to close upon the shuttle so as to reverse its direction, it becomes instantly released from pressure owing to the formation and eccentricity of the "swell." The action of the shuttle when entering the box also forces back the swell and its supporting rod, which, with every complete "pick," raises a lever on the stop-rod, and prevents it coming into contact with the "frog" of the loom, which it otherwise would do if the shuttle did not enter the box, the effect of which would be to stop the loom.

In order that the invention may be better understood and explained in detail we have hereunto attached a sheet of drawings, similar letters of reference being marked thereupon:

Fig. 1 is a sectional plan view of sufficient of a loom to show our improvements.

Fig. 2, a section on the line 1-2, fig. 1.

Fig. 4, a section on the line 4-4, fig. 1; and

Fig. 3, an inverted plan view.

C is the shuttle-box which is secured to the "slay" in a manner too well known to those skilled in this class of machinery to need description.

Through openings in the back and front of the shuttle-box protrude the frictional pick bowls c c, the latter being secured upon the vertical spindles f f, which are supported and rest on the movable lever bearings g g. These bowls are driven at a high velocity, through the arrangement of pulleys i, which receive their motion from a pulley on the crank shaft. In conjunction with the rapidly revolving motion a second motion is imparted to them by the wedge k through the medium of the lever l. This wedge is actuated in such a manner by any suitable mechanism that with each alternate pick it is caused to be inserted so as to force asunder the lever bearings g g, thereby at such time causing a greater opening or division between the peripheries of the picking

bowls, so as to allow the shuttle freely to enter the shuttle-box. The shuttle, when passing the picking bowls upon its entrance into the box, is effectually and gradually checked in its progress by the eccentric "swell" *o*, the peculiar formation and action of which is more clearly described hereinafter. The picking bowls, immediately the shuttle is brought to a stand, are caused, by the withdrawal of the wedge from the bearings of the spindles upon which they are secured, to press against the sides of the shuttle, the frictional contact of which has the instantaneous effect of expelling the same across the loom into the opposite box, where it is received and expelled again in like manner, and so on *ad libitum*.

The eccentric "swell" *o* is supported and turns freely on the finger *p*, which is attached to the stop-rod *g* of the loom. The spring *i*, which bears on an arm, *b*, of the stop-rod, causes the swell, when at rest, slightly to protrude through the aperture *s* in the back board of the shuttle-box. A lever on the stop-rod actuates the frog so as to stop the loom (when the weft is broken or the cop spent) in the usual manner. The action of the improved eccentric swell from the foregoing lettered description may be thus described: Upon the shuttle entering the box its frictional contact with the swell causes such swell by its eccentric formation to turn and exert an increasing pressure upon the shuttle until it is finally checked and brought to a stand, but immediately the slightest outward action is brought to bear upon the shuttle, whether by the ordinary picker or our improved picking bowls, the eccentric swell, with its reverse action, instantly releases the shuttle from pressure, thereby reducing the strength of pick required, and causing a less wear and tear to the shuttles employed. The pressure of the shuttle against the swell or entering box also forces back the finger *p*, secured to the stop-rod, and so operating the latter and the devices connected therewith as to prevent the motion of the loom from being interrupted, as it would be if the shuttle did not enter the box.

Having now described the nature of the said invention, together with the method of carrying the same into practical effect, we wish it to be distinctly understood that we claim—

First, the novel and peculiar arrangement of mechanism described for expelling the shuttle of looms from one box into the other, and *vice versa*, without the use of the picker as now employed for the same purpose. And

Secondly, we claim the "eccentric swell" and the apparatus in connection therewith for gradually and effectually checking the shuttle upon its being received by the shuttle-box, and also for instantly releasing the same upon its expulsion, as hereinbefore described, set forth, and fully illustrated in the drawings attached.

In testimony whereof we have hereunto signed our names to this specification in the presence of two subscribing witnesses.

JOSEPH JOHN HARRISON,
EDWARD HARRISON.
